CLAIM

The ornamental design for a combined shower caddy and toilet kit, as shown and described.

DESCRIPTION

FIG. 1 is a combined shower caddy and toilet kit showing our new design;

FIG. 2 is a left side elevational view thereof;

FIG. 3 is a reduced perspective view thereof, showing the kit in an alternative position;

FIG. 4 is a right side elevational view thereof;

FIG. 5 is a top plan view thereof; and

FIG. 6 is a bottom plan view thereof.
